UNITED STATES PATENT OFFICE

2,264,648

EXPLOSION ENGINE

Alessandro Tebaldi, Milan, Italy

Application August 16, 1938, Serial No. 225,243
In Germany August 30, 1937

3 Claims. (Cl. 123—55)

This invention relates to multi-cylinder four stroke explosion engines particularly of high power class, and it comprises an engine in which an explosion chamber cooperates with two or more cylinders arranged at an angle to each other, the pistons operative in said cylinders actuating crank shafts mounted adjacent the ends of respective cylinders remote from said explosion chamber.

In a preferred embodiment of the engine of this invention it includes one or more sets of radially or star arranged cylinders located at an angle to each other the cylinders of each set having their common explosion chamber in the central portion of the engine while the respective crank shafts are located at the periphery of the engine and impart their rotation to a main driving shaft or to a number of main driving shafts.

The present invention thus provides an engine which has a large number of cylinders as useful to reduce the size and weight of the reciprocating masses, the load operative on the bearings and the extent of the piston strokes, while at the same time it includes a restricted number of explosion chambers with the advantage of an improved thermic efficiency and of a more simple organization of the distributing gears.

Some embodiments of this invention are illustrated on the annexed drawings and—

Fig. 1 is a transverse section of an engine of this invention with four radial cylinders said section being made on a plane extending through the cylinder axes;

Fig. 2 is a similar section of an eight radial cylinder engine;

Fig. 3 shows diagrammatically the respective position of the mouths of four cylinders providing a cylinder set as opening in the cooperating explosion chamber;

Fig. 4 is a diagrammatic view similar to Fig. 3 in connection with a modified arrangement of cylinders;

Fig. 5 is a transverse section of an eight-cylinder engine divided in four sets with an explosion chamber cooperating with each cylinder set;

Fig. 6 is a section of an engine with four fan-arranged cylinders;

Fig. 7 is a section of an engine including six star arranged cylinders and made on line 7—7 of Fig. 8;

Fig. 8 is a side view with parts in section of an engine including 36 cylinders arranged in six star-groups each similar to that illustrated in 55

Fig. 7, said section being substantially on the line 8—8 of Fig. 7;

Fig. 9 is a side view with parts in section of an engine similar to that illustrated in Fig. 8 with a modified valve arrangement;

Fig. 10 is a diagrammatic perspective view of the transmission gear intermediate the shafts each cooperating with the piston or pistons of a cylinder or of a cylinder row and a central driving shaft in connection with engines of the class shown in Figs. 8 and 9;

Fig. 11 is a diagrammatic side view with parts in section of an engine including two concentric driving shafts and

Fig. 12 is a diagrammatic perspective view of the transmission gear intermediate the crank shafts cooperating with the cylinder pistons and the central driving shafts.

In the embodiment of Fig. 1, the reference 1 is affixed to a structure in which four cylinders 2, 3, 2', 3' are located, said cylinders being arranged in two sets; one of said sets includes the two cylinders 2, 3 which extend from a casing 4 which provides an explosion chamber 5. Pistons 6 and 7 reciprocate in the cylinders 2 and 3 and their respective connecting rods 8 and 9 engage crank shafts 10 and 11 supported as conventional in respective crank cases 32 and 33.

A casing 4' is arranged opposite to and spaced from casing 4 and said casing 4' carries a pair of cylinders 2', 3' which radiate from the casing 4' and are opposite and aligned with respect to cylinders 2, 3, said cylinders 2', 3' opening in an explosion chamber 5' provided by said casing 4'. The pistons 6' and 7' of the cylinders 2', 3' are connected by the respective rods 8', 9' with crank shafts 10', 11' supported in respective crank cases 32', 33'.

A drum 34 is provided intermediate the two casings 4, 4' enclosing the explosion chambers 5, 5'; in said drum a rotary distributor or valve 12 is located which has at one end a pinion 13 meshing with a pinion 14 fast on a shaft 15 driven by the intermediate of pinion 35, 36 and shaft 19, the means for actuation of shaft 19 by a main driving shaft of the engine being herein-after described.

The distributor 12 provides two side ports 12' which when said distributor is rotated are carried in timed succession in front of the mouths 5'' of chambers 5 and 5' and lead respectively to an inlet duct 16 connected with a conventional source of explosive fuel mixture and with an outlet 17.

Means as ducts 37 and 38 provide for a fluid

circulation through the intermediate space 12' of said sleeve 12 for the purpose of cooling it.

Said distributor 12 is driven in rotation with a rotary speed which may be one fourth or one half of the rotary speed of the crank shafts 10, 11, 10', 11'; accordingly an explosion occurs at the same time in both chambers 5, 5' each two revolutions of said crank shafts or explosions will occur alternately in said chambers 5, 5' one at each revolution.

Of course suitable conventional ignition means as a plug 46 provided to promote the ignition of the operative mixture in said chambers 5, 5'.

The four crank shafts 10, 11, 10', 11' are connected with a single central driving shaft or with two separate driving shafts by means of a gearing as hereinafter described.

During the operation the usual operative cycle of four stroke explosion engines develops separately in each of the two chambers 5, 5' each of which is common to a set of two cylinders. Consequently each explosion in each chamber causes a stroke in the same direction and through the same extent of the two pistons of the co-operating cylinder set; the power development is thus shared on two separate sets of mechanical transmission gears.

The arrangement is such as the two crank shafts of each set as 10 and 11 are revolving in opposed directions; each system comprising a piston, a rod, a crank and a crank shaft as 6, 8, 10 thus develops on the structure 1 comprising the co-operating cylinders, crank shaft bearings and crank cases, as 2, 32 and 2', 32', stresses which are at any time equal and directly opposed to stresses developed on said structure by a similar system as 6', 8', 10' which operates in the opposed direction; accordingly in the whole star cylinder structure all the stresses compensate for each other and said star structure is balanced.

The engine shown in Fig. 2 is similar to that described in respect of Fig. 1 but four cylinders cooperate with each explosion chamber and more particularly the cylinders 2, 3, 3a, 2a radiate from casing 4 providing an explosion chamber 5 and the cylinders 2', 3', 3'a, 2'a radiate from casing 4' providing the chamber 5' said cylinders being diametrically opposed two by two with respect to a centre line intermediate the casings 4, 4' and coextensive therewith.

A drum 34 having ports 5'' is provided intermediate said casings 5, 5' and a rotary distributor 12 cooperates with it, the arrangement and actuation of the distributor 12 being made as described in connection with Figure 1.

In the illustrated construction the arrangement is such as the crank shafts 10, 11, 11a, 10a and 10', 11', 11'a, 10'a of each cylinder set which are connected by rods 8, 9, 9a, 8a and 8', 9', 9'a, 8'a with the pistons 6, 7, 7a, 6a and 6', 7', 7'a, 6'a rotate in pairs in opposed directions as shown by the arrows in Fig. 2.

In the arrangement of Fig. 2 the cylinders 2, 3, 3a, 2a and 2', 3', 3'a, 2'a may be arranged with their axes in a single plane as evidenced by the diagram of Fig. 3 which shows in perspective the respective positions of the mouths of the cylinders 2, 3, 3a, 2a in the casing 4; should it be desired to reduce the angular span of the explosion chambers 5, 5' said cylinders of each group may be staggered or lie in adjacent parallel planes as shown in Fig. 4 in respect of cylinders 2, 3, 3a, 2a in the above defined manner.

Fig. 5 illustrates another embodiment of an

eight-cylinder star arrangement in which the cylinders of a set as 2, 3, 3a, 2a are not radially arranged and they do not lie on the extension of the axis of the respective cylinders 2', 3', 3'a, 2'a of the other set to provide pairs therewith.

In this construction two explosion chambers as 5, 5a, and 5', 5'a are provided in respect of each cylinder set, each of said chambers cooperating with two cylinders.

10 As above described the explosion chambers provide a drum 34 for a rotary distributor 12 driven by the shaft 15 as above described. The mixture inlet duct 16 is located with advantage intermediate the pairs of adjacent explosion chambers 5, 5a, 5', 5'a while the exhaust occurs through the central outlet 17 of said distributor.

The arrangement in this construction is such as the shafts 10 and 11 of the cylinders 2, 3 of the set cooperating with explosion chamber 5 rotate both in the same direction, while the crank shafts 11a, 10a of the set of cylinders 3a, 2a co-operating with the explosion chamber 5a revolve in the same direction this direction being opposed to that of crank shafts 10 and 11; similar respective conditions exist in connection with the cylinders of the opposed sets. The whole star structure is thus balanced.

Instead of having two opposed cylinder sets as in the above described embodiments, a single set of cylinders extending from one or more explosion chambers each common to two cylinders at least, may be used.

Such an arrangement of the cylinders which may be referred to as a fan arrangement, is illustrated in Fig. 6; this embodiment includes four cylinders 2, 3, 3a, 2a radiating from a casing 4 which provides an explosion chamber 5, while the other parts are similar to those of above described embodiments and are similarly referenced.

Figure 7 illustrates an embodiment in which each cylinder set cooperating with one and the same explosion chamber as 5, 5' includes three cylinders 2, 3, 3a, 2', 3', 3'a in which pistons 6, 7, 7a, 6', 7', 7'a reciprocate, said pistons actuating the crank shafts 10, 11, 11a, 10', 11', 11'a, by means of connecting rods 8, 9, 9a, 8', 9', 9'a.

The two cylinder sets are carried by a single structure 1 and are provided with a rotary distributor 12 actuated by a shaft 15 in the above described manner; the two cylinder sets are rigidly interconnected say by means of the rods 18, to entirely balance the actions developing in each star structure 1.

55 In any case the engine may include a number of star sets or of fan sets arranged at the side of each other, their adjacent cylinders providing a number of aligned rows.

Figure 8 illustrates by way of example an engine which includes six star sets each of the type shown by Fig. 7 and having a rotary distributor 12; all said distributors are actuated through the intermediate of respective shafts 15 by a shaft 19 (Fig. 7) which extends along the engine on a side thereof.

Fig. 9 illustrates an arrangement in which the distributor is arranged longitudinally of the engine and on the axis thereof. Further, in this construction the engine includes six star-cylinder structures each including two sets of three cylinders of the kind shown in Fig. 7; a drum 20 extends along the whole of the star sets and a distributor sleeve 21 is mounted to rotate within said drum, said sleeve being driven by one of the 70 crank shafts, as 11a, through the intermediate

of a train of pinions 22. Said sleeve 21 is connected with the source of explosive mixture (not shown) and in register with ports 5' of the explosion chambers of each star set it has ports 23 adapted to connect the explosion chambers with the mixture source and also ports 39 adapted to connect said explosion chambers with side outlet ports 24, suitable partitions as 40 being provided within the distributor sleeve to separate inlet and outlet spaces therein; self explaining means as 41, 42, 43, 44 are provided at the free end of said sleeve 21 for supporting it and providing a cooling circulation therein.

As to the transmission of the power developed by the several cylinder sets or rows, the pistons of all the cylinders aligned with each other in the several adjacent sets are connected with a single crank shaft and thus each row of cylinders operate like an engine having aligned cylinders.

Each of said crank shafts is provided with pinions 25, 25' (Figs. 8 and 9) which impart the drive to one or more shafts which provide the engine driving shaft or shafts.

The transmission gear between each of said crank shafts and said main driving shaft or shafts must be designed to comply with the requirement that one half of said crank shafts must rotate in one direction and the other half must rotate in the opposite one.

In the construction of Figs. 8 and 9 the engine includes a single main or driving shaft 26 having a pinion 27 fast thereon which meshes with the pinions 25 of a number of said crank shafts while the pinions 25' of the other crank shafts drive the pinion 27 by the intermediate of a reversing pinions 28, 29 geared intermediate the pinions 25' and 27.

Figure 10 shows diagrammatically and in perspective view the above stated transmission gear, said figure displaying only two crank shafts 11'a and 11'a intended to rotate in opposed directions. The pinion 25 fast on the shaft 11'a is directly in mesh with the central pinion 27 fast with the shaft 26 while the pinion 25' of the shaft 11'a meshes with another pinion 28 fast with an identical pinion 29 which meshes with the pinion 27. In the described conditions all the crank shafts of the engine impart their drive to shaft 26. Pinion 45 driven by the pinion 27 actuates a shaft 19 for the actuation of the distributing means as above referred to.

If it is desired to have two main shafts revolving in opposed directions, the pinions 25, 25' of each set of crank shafts revolving in a given direction mesh with a main pinion solid with one of said main shafts; said main pinions are further engaged together by a suitable gear to comply with the obvious requirement that the rotation of said oppositely rotating main shafts must be synchronous.

Figure 11 illustrates an engine having two concentric main shafts 26, 26' which are required to rotate in opposed directions and which have pinions 27, 27' fast thereon respectively the pinion 27 being engaged by the pinions 25 which rotate all in one given direction whilst the pinion 27' is engaged by all the pinions 25' which rotate in the opposed direction; said shafts 26, 26' are interconnected by a gear adapted to secure their synchronous rotation as hereinafter described in connection with Fig. 12.

In Fig. 12, two pinions 25 and 25' fast on reversely rotating crank shafts 16'a, 16'a and two pinions 27, 27' fast with main driving shafts 26, 26' respectively, are illustrated. The pinion 25

meshes with the pinion 27 and the pinion 25' is in mesh with pinion 27'; further pinions 30 and 31 are provided which are fast with each other and have a diameter equal to that of pinions 25, 25'; the pinion 30 is in mesh with the main pinion 27 while pinion 31 is in mesh with the pinion 25'.

By the described arrangement the pinions 25, 25' are engaged angularly with each other by the gearing 27, 30, 31 and thus the main shafts 26, 26' rotate in opposed directions with an equal number of revolutions per minute.

The described engine is adapted to develop very high powers in satisfactory conditions in respect of the construction, weight and balance of the engine, while the number of the parts devoted to distribution and ignition are reduced to a minimum. Further the cooling of engine which may be secured by water jackets or air circulation is made more simple and the power output may be taken off in different manners according to requirements.

What I claim as my invention and desire to secure by United States Letters Patent is:

1. A multi-cylinder explosion engine comprising a casing providing a number of adjacent chambers at each of opposite sides thereof, means for timely connecting each of said chambers with an operative fluid inlet and outlet, means for igniting said fluid in each of said chambers, sets of cylinders radiating from said casing, each of said sets including for each of said chambers a number of cylinders adjacent to each other and opening at one of their ends in the same end of the respective chamber, crank-cases each at the casing-spaced ends of one of said cylinders, crank-shafts each in one of said crank-cases, pistons each reciprocating in one of said cylinders, rods connecting the pistons of said cylinders with said crank-shafts of the respective crank-cases, at least a power output shaft, and means connecting said power output shaft with said crank-shafts.

2. A multi-cylinder explosion engine comprising an elongated casing providing a number of adjacent chambers located at each of opposite sides thereof and in a succession extending in the longitudinal direction of said casing, means for timely connecting each of said chambers with an operative fluid inlet and outlet, means for igniting said fluid in each of said chambers, sets of cylinders radiating from said casing, each of said sets including for each of said chambers a number of cylinders adjacent to each other and opening at one of their ends in the same end of the respective chamber, said cylinders of said sets providing a number of parallel rows extending along said casing, crank-cases each at the casing-spaced ends of said cylinders of one of said rows, crank-shafts each in one of said crank-cases, pistons each reciprocating in one of said cylinders, rods connecting the pistons of said cylinders of each of said rows with said crank-shafts of the respective crank-cases, at least a power output shaft and means connecting said power output shaft with said crank-shafts.

3. A multi-cylinder explosion engine comprising an elongated casing providing a number of adjacent chambers located at each of opposite sides thereof and in a succession extending in the longitudinal direction of said casing, means for timely connecting each of said chambers with an operative fluid inlet and outlet, means for igniting said fluid in each of said chambers, sets of cylinders radiating from said casing, each of said sets including for each of said chambers

an even number of cylinders adjacent to each other with their axes substantially co-planar and opening at one of their ends in the same end of the respective chamber, said cylinders of said sets providing a number of parallel rows extending along said casing, crank-cases each at the casing-spaced ends of said cylinders of one of said rows, crank-shafts each in one of

5 said crank-cases, pistons each reciprocating in one of said cylinders, rods connecting the pistons of said cylinders of each of said rows with said crank-shafts of the respective crank-cases, at least a power output shaft, and means connecting said power output shaft with said crank-shafts.

ALESSANDRO TEBALDI.
